W. H. BORDEN,
FASTENING SUPPLYING MECHANISM.
APPLICATION FILED APR. 25, 1918.

Patented Nov. 11, 1919.

Fig.3. Fig.4.

INVENTOR -
William H. Borden.

UNITED STATES PATENT OFFICE.

WILLIAM H. BORDEN, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-SUPPLYING MECHANISM.

1,321,186.

Specification of Letters Patent. Patented Nov. 11, 1919.

Original application filed December 16, 1914, Serial No. 877,596. Divided and this application filed April 25, 1918. Serial No. 230,750.

To all whom it may concern:

Be it known that I, WILLIAM H. BORDEN, a citizen of the United States, residing at Winchester, in the county of Middlesex and

5 State of Massachusetts, have invented certain Improvements in Fastening-Supplying Mechanism, of which the following description, in connection with the accompanying drawings, is a specification, like reference 10 characters on the drawings indicating like parts in the several figures.

This invention relates to fastening supplying mechanisms for use in connection with fastening driving machines and particularly 15 to supplying mechanisms for handling protectors of the type known to the trade as "tadpole" protectors. These protectors, which are designed to be driven into the soles or heels of boots and shoes, have each 20 a head portion comprising laterally extending wings shaped to embrace the stock into which the protector is driven and a shank 25 depending from the head between the wings, a protector of this type being shown in 30 United States Letters Patent No. 889,383, granted to S. D. Leland, June 2, 1908.

It is an object of the present invention to provide means adapted to receive the protectors in bulk and operative to arrange 35 them with their wings similarly positioned and to maintain them in this position relatively to each other while they pass to driving position.

In furtherance of this object, there is provided an assorting device for positioning the protectors on the raceway with their shanks projecting into the slot of the raceway and their wings extending uniformly in one direction. Means are also provided for maintaining the protectors in the said position 40 as they pass to driving position. Preferably the raceway itself is so constructed as to perform this function of maintaining the protectors in the position described.

45 Inasmuch as the protectors are delivered in quantity upon the upper end of the raceway, it occasionally happens that they will lodge improperly on the raceway and move along the same. Accordingly, there is provided an improved kick-off device to remove 50 such misplaced protectors. Preferably said device is mounted independently of the raceway and bears upon the upper side thereof.

This application is a division of application Serial No. 877,596, filed December 16, 55 1914, for improvements in fastening inserting machines.

The above-mentioned and other features of the invention will be understood from the following specification which discloses 60 in connection with the drawings one embodiment of my invention.

Figure 1 is a front end elevation of the upper part of the machine with the movable body of the hopper detached; 65

Fig. 2 is an enlarged plan view of the raceway detached from the machine; the raceway cover being removed;

Fig. 3 is a section on the line 3—3, Fig. 1;

Fig. 4 is a section on the line 4—4, Fig. 70 1; and

Fig. 5 shows in side and front elevation and in plan one of the novel protectors which the machine to be herein described is particularly adapted to handle. 75

The invention may be embodied in nailing machines of various types, but is herein shown, for convenience, as applied to a nailing machine of the type shown and described in United States Patent No. 490,624 dated 80 Jan. 24, 1893.

In the drawings, the swinging frame 6, the foot plate 7, the driver bar 8, the awl bar 12, the rotatable hopper 13, the separator lever 15, the means for actuating the driver bar and the awl bar, the means for imparting lateral movement to the frame 6 that the awl may feed the stock, and means for rotating the hopper and for actuating the lever 15, may be substantially as shown and fully 90 described in said Patent No. 490,624.

To enable protectors having depending shanks to be controlled and driven by the machine referred to, a novel raceway is provided. This raceway comprises front and 95 rear walls or plates 17, 18, with an assorting device 19 shown as a plate rising above the rear wall 18 of said raceway, the assorting device being held in place by suitable screws 20 extending through the front wall 100 17 of the raceway, said screws also passing through a standard 24 which sustains the shelf 21.

The assorting device 19 is located opposite the lower end of the shelf 21 and projects 105 above the same, the face of said device form-

ing a continuation of the face of the rear wall 18 of the raceway. The upper end of the front wall 17 is separated quite a distance from the rear wall 18 by spacing blocks 5 22, so that the shank of a protector can freely enter the passageway between said walls, with the underside of the laterally extending wings of its head resting upon the edge of the front wall 17, the passageway being not wide enough to permit the head of the protector to pass therethrough. The upper end of the front wall 17 is beveled on opposite sides from a sharp to a gradual bevel, as shown in Figs. 2, 3 and 4, so that 10 it is impossible for a protector to hang upon said front wall unless the shank of the protector projects into the passageway between the front and rear walls, consequently only those protectors will be positioned properly 15 which drop from the shelf 21 with their shanks projecting downwardly and with the laterally extending wings of their heads projecting away from the assorting device 19. All of the other protectors, namely, those 20 which drop from the shelf head first or with their laterally extending wings projecting toward the assorting device, will engage the beveled portion of the front wall and be deflected into the hopper. The rear wall 18 25 of the raceway is slightly higher than the front wall 17 and is adapted to be engaged by the outer side of the head of the protector, so as to prevent the protector from turning as it travels down the raceway with its 30 shank projecting into the passageway and with the underside of its laterally extending wings resting upon the edge of the front wall. The front and rear walls of the raceway are held together by screws 23, spacing 35 blocks being interposed between the walls to determine the width of the passageway. At the extreme upper end of the raceway, resting upon the front wall 117 is a block 40 25 which is fastened to the assorting device by screws 26, as shown in Fig. 1.

The raceway near its upper or receiving end is provided, see Fig. 2, with a contracting device, herein shown as a plate 27 adjustably secured by suitable screws 28 to the 45 rear wall 18 of the raceway, said device being made adjustable to enable the width of the raceway groove which receives the shanks of the protectors, to be varied. By adjusting the plate 27, the width of the raceway groove at the entrance thereto may be 50 made to correspond to the thickness of the shank of the protector, so that only those protectors will pass through the entrance to the raceway which present the edges of 55 their shanks to the groove of the raceway, thus causing the protectors to occupy a position on the raceway with the under sides of their heads resting on the top of the wall 17 and with the wings of the protectors extending in the same direction.

Bearing upon the raceway near the contracting device is a kick-off, shown in Figs. 1 and 4 as a lever 29 pivoted on a screw 30 in the stationary part 32 of the hopper, a suitable spring 33 acting to keep the longer 70 end of the kick-off normally pressed against the upper side of the rear wall 18 of the raceway.

The raceway is connected to and reciprocated with the swinging frame 6 as the latter is moved to effect the feeding of the stock. As the raceway is reciprocated any protectors having their shanks but partially in the raceway groove, or any protectors which are 75 lodged improperly on the raceway, are 80 struck by the kick-off and dislodged from the raceway.

Having described my invention, I claim as new and desire to secure by Letters Patent of the United States:—

1. In a machine for driving protectors having depending shanks, a raceway comprising front and rear walls spaced apart to receive and guide the shank of a protector, the rear wall of the raceway being adapted 90 to engage the rear portion of the head of the protector and the front wall being adapted to sustain the underside of the head of the protector.

2. In a machine for driving protectors having depending shanks, a slotted raceway having mounted near the upper end thereof an adjustable device that is adapted to control the entrance into the slot in the raceway below said device of only those protectors 100 which have shanks of the desired thickness.

3. In a machine of the class described, a raceway for fastenings, a hopper in which the raceway is movable, and a kick-off sustained independently of the raceway and bearing 105 on the upper side of the raceway, and operative on movement of the raceway to dislodge fastenings improperly supported on the raceway.

4. In a machine of the class described, a 110 raceway, a hopper in which the raceway is movable, a kick-off bearing on the upper side of the raceway, and yielding means for keeping the free end of the kick-off seated on the raceway, said kick-off being operative 115 on movement of the raceway to dislodge fastenings improperly supported on the raceway.

5. In a machine of the class described, a raceway comprising front and rear walls, 120 the edge of the front wall at the upper end of the raceway being beveled on opposite sides, and the rear wall having mounted thereon an assorting device located opposite the beveled portion of the front wall.

6. In a machine for driving winged protectors having depending shanks, a shelf for sustaining the protectors, a raceway provided with a slot for receiving the shanks of the protectors as they drop from said shelf, 130

and means for preventing the entrance into said slot of the shanks of any protectors which, upon leaving the shelf, have their wings projecting away from the shelf.

- 5 7. In a machine for driving winged protectors having depending shanks, an inclined shelf for sustaining the protectors, a slotted raceway for receiving the protectors as they drop from said shelf, and an assort-
10 ing device for positioning the protectors on the raceway with their shanks projecting into the slot and their wings extending in a uniform direction.
8. In a machine for driving winged pro-
15 tectors having depending shanks, a slotted raceway constructed to receive and guide

the shanks and sustain the undersides of the heads of a series of protectors, said raceway acting to keep the protectors with their wings extended in the same direction. 20

9. In a machine of the class described, a movable raceway having a slot to receive the shanks of protectors, a shelf, an assorting device arranged opposite said shelf, and a kick-off arranged to operate upon move- 25
ment of the raceway to dislodge protectors improperly placed on said raceway, substantially as described.

In testimony whereof I have signed my name to this specification.

WILLIAM H. BORDEN.
